(57) **CLAIM**

The ornamental design for a display positioning device, as shown and described.

DESCRIPTION

FIG. 1 is a top perspective view of a display positioning device showing the new design.

FIG. 2 is a bottom perspective view of the display positioning device showing the new design.

FIG. 3 is a front view of the display positioning device showing the new design.

FIG. 4 is a back view of the display positioning device showing the new design.

FIG. 5 is a left side view of the display positioning device showing the new design.

FIG. 6 is a right side view of the display positioning device showing the new design.

FIG. 7 is a top down view of the display positioning device showing the new design; and,

FIG. 8 is a bottom up view of the display positioning device showing the new design.

Within the drawings, the dotted lines, the dot-dash lines, and the areas within the dotted or dot-dash lines show unclaimed portions of the display positioning device, and form no part of the claimed design.
